Fig. 15.

1 Inventor

This technical drawing illustrates a water treatment system, likely a sedimentation and filtration unit. The system is arranged in two parallel rows of tanks. The top row consists of four tanks, each with a circular bottom and a flat top. The bottom row consists of three tanks, also with circular bottoms and flat tops. Between the two rows of tanks are two rectangular structures, each containing two circular components, possibly filters or pumps. The piping system is complex, with numerous valves, fittings, and pumps. Handwritten numbers are used to label specific components: 1, 5, 13, 34, 35, 36, 37, 40, 43, 44, 45, 48, 49, 50, 51, 55, 56, 58, 59, 60, and 7. There are also handwritten labels '34' and '38' near the top and bottom tanks respectively. A vertical hatched line on the right side is labeled '37' at the top and '38-' at the bottom. A vertical line on the far left is labeled '2' at the top and '3' at the bottom.

UNITED STATES PATENT OFFICE.

GEORGE STRONG WITHAM, SR., AND GEORGE STANFORD WITHAM, JR., OF HUDSON FALLS, NEW YORK.

TEMPERATURE CONTROL IN PAPER DRYING.

Application filed March 31, 1921. Serial No. 457,304.

To all whom it may concern:

Be it known that we, GEORGE S. WITHAM, Sr., and GEORGE S. WITHAM, Jr., residing at Hudson Falls, in the county of Washington, 5 State of New York, whose post office address is % Union Bag & Paper Corporation, Hudson Falls, New York, have invented certain new and useful Improvements in Temperature Control in Paper Drying; 10 and we do hereby declare the following to be a full, clear, and exact description of the invention, such as will enable others skilled in the art to which it appertains to make and use the same.

15 Our invention is an improvement in temperature controls for paper making machines, and relates especially to mechanism for controlling the temperature of the rolls over which the paper web is drawn to dry 20 the same, after it has been formed.

An object of the invention is to provide, in connection with the drying cylinders of a paper making machine, means for maintaining the temperature of the cylinders 25 substantially uniform, and controlled by the temperature of certain of the cylinders.

Another object is to provide means for heating the cylinders to progressively higher 30 temperatures from the wet to the dry end of the dryer, and controlled by the temperature of selected cylinders.

Another object is to provide in a paper 35 making machine, mechanism for heating the drying cylinders with exhaust steam, controlled by the temperature of the rolls, and auxiliary heating means also controlled by the temperature of the rolls, for supplementing the exhaust steam, when necessary to maintain a uniform temperature.

40 Another object is to provide in machines of the character wherein the drying cylinders are heated by exhaust steam, means controlled by the temperature of selected cylinders, for varying the quantity of steam admitted to the rolls in accordance with the temperature desired.

Another object is to provide mechanism in connection with the controlling means for adjusting the same to provide for any desired temperature of the cylinders.

Another object is to provide means normally operative for closing the discharge end of the exhaust steam manifold and controlled to open position when the live steam supply is connected to the cylinders,

Another object is to provide in connection with the exhaust steam manifold, a relief valve, adapted to open when the pressure exceeds a predetermined amount, and a normally closed valve between the said manifold and the feed water heater, controlled to open position when the live steam supply is connected to the cylinders. 60

A further object is to provide mechanism for separating the liquid of the condensate 65 from the air and vapor, and for removing the liquid from the cylinders as it forms.

Another object is to provide a series of means, arranged at intervals between the drip header for the cylinders and the return 70 pipe, for connecting said header to the pipe, and means for operating the said connecting means, to connect and disconnect the header and the pipe, controlled by the level of the liquid, and operated by fluid under pressure. 75

In the drawings;

Figures 1^a and 1^b, taken together, show in diagrammatic form and conventionalized the heating system of a set of drying rolls,

Figures 2^a and 2^b, together, constitute a 80 similar view of the mechanism for collecting the condensate and returning it to the feed water heater.

Figure 3 is a vertical section through one 85 of the controlling units,

Figure 4 is a section on the line 4—4 of Figure 3,

Figure 5 is a vertical section through one 90 of the controlling valves,

Figure 6 is a similar view of one of the 95 separators.

In the usual construction of paper dryers wherein the heating rolls or cylinders are heated by steam, the control of the temperature functions upon variations of steam 100 pressure, or upon changes in tension of the paper. Because of the fact that a certain pressure does not always mean a definite temperature of the heating cylinders, controls based upon the pressure do not give 105 the desired results. The same is true concerning those controls which depend upon the tension of the paper, for they do not function when no paper is running. A definite steam pressure in the manifold does 110 not produce corresponding temperatures in the cylinders, due to conduction, condensation, poor circulation and air pocketing. In the present invention the supply of heating medium is controlled directly by the tem., 110

2

perature in selected cylinders, and mechanism is provided for ridding the system of entrapped air and for quickly removing the condensate. The temperature control is shown in connection with the dryer of a paper making machine, the said dryer consisting of a number of cylinders 1 of usual construction, about which the paper web is drawn to remove the moisture. The cylinders are supplied with a heating medium, in the form of exhaust steam, from an exhaust steam header 2. The cylinders are arranged in sets of seven in the present instance, and each set of cylinders is supplied with steam from a manifold 3. Supply pipes 4 lead from the manifold to the cylinders, extending into the cylinders at the axis thereof and at one end of the cylinder, in a usual and well-known manner. The header 2 is connected to each manifold section 3 by means of a supply pipe 4, and in each of these supply pipes there is arranged a cut-off valve 5, and a controlling valve 6 arranged within a valve casing 7, which is interposed in the length of the pipe. Cut-off valves 8 are arranged between the sections of the manifold, so that all of the sections may be connected if desired. Each of the valves 6 has connected therewith a stem 9, and the end of the stem remote from the valve is connected to a diaphragm 10 which is arranged within a casing 11 supported by the valve casing 7. A spring 12 is arranged between each stem and the casing 7, and acts normally to hold the valve open, as shown in Figure 5. The casing 11 forms with the diaphragm a closed compartment, and fluid under pressure is admitted to this compartment, under circumstances to be presently set forth, for closing, or partially closing, the valve, against the resistance of the spring. Fluid under pressure is supplied to the several casings 11 by means of pipes 13, and the supply of fluid under pressure is controlled by mechanism to be described.

Within a selected cylinder of each series there is arranged a thermostatic bulb, each of which is adapted to contain a liquid volatile at ordinary temperatures, as for instance ether. The bulb is not entirely filled, and hence contains partly vapor and partly liquid. Each bulb is connected by a pipe 14 with an expansible and contractable casing or capsule 15. Each capsule or casing is resilient, so that it will expand or contract in accordance with the expansion and contraction of the liquid, and each capsule is supported in fixed position within a substantially cylindrical casing 16 having a circular observation opening normally closed by a plate 17 of transparent material, as for instance glass. A lever 18 is pivoted intermediate its ends to a bracket 19 in the casing 16, and through this lever there is

threaded a screw 20 whose inner end engages one side wall of the capsule 15. A spring 21 is arranged between the lever and the base of the casing 16, on the opposite side of the bracket 19 from the screw 20. This spring engages a pin 22 on the casing 16, at one end of the spring, and the other end of the spring is engaged by a set screw 23 threaded through the lever, the set screw permitting the tension of the spring to be varied. The outer end of the screw 20 is polygonal as shown, and the screw is coaxial with an eyelet 24 which is arranged at the center of the sheet 17. Through this eyelet access may be had to the screw to turn the same, whereby to regulate the extent of movement of the lever under the influence of the diaphragm. The position of the screw is indicated by means of an indicator 25 fixed to the screw, and cooperating with a scale on a dial 26 held by the lever.

Two types of controllers are used, differing from each other only in the number of valves which they control. In the simplex type, each lever 18 controls one valve, while in the duplex type, one of which is shown in Figure 3 the lever controls two valves. In this construction, the valves 27 and 28 are connected to the lever by means of stems 29, the stems being held to the lever by nuts as shown. Each stem passes through a packing nut 30 between the valve and the lever. The pipe 13 which leads from the source of supply of fluid under pressure is interrupted at the casing 16. The ends of the pipe at the said casing are connected by a passage consisting of portions 31 and 32 offset laterally with respect to each other. At one end of the connecting portion between the offset portions of the passage there is provided a seat 33 with which the valve 27 cooperates, and the inner end of the packing nut 30 is recessed as shown, to receive the valve, to permit it to fully open. The construction at the valve 28 is precisely the same. In the simplex construction the valve 28 is omitted.

As shown in the drawings, the dryer is divided into four sections, the cylinders of each section receiving steam from a manifold section 3. Each manifold section is connected to the exhaust steam header 2 by a pipe 4, and each pipe 4 is controlled by a valve 6. The sections are intended to be heated to progressively higher temperatures, from the wet to the dry end of the dryer. In the present arrangement means is provided for supplementing the exhaust steam with live steam, and such means is controlled by the temperature controlling mechanism just described in those two sections of the dryer which are at the dry end of the dryer. The live steam is supplied by a pipe 34, which has branches 35 leading to the pipes 4 of the two sections of the dryer at

the dry end. These branch pipes 35 open into the pipes 4 between the valves 6 and the manifold sections 3, and each branch is controlled by a valve 6, arranged in a casting 7, which is interposed in the branch adjacent to the pipe 4. A cutout valve 36 is arranged in each branch, between the casting 7 and the supply pipe 34. The pipes 13 which supply fluid under pressure to the 10 diaphragm chambers of the casings 11 controlling the valve 6 of the branches 35, are controlled by the valve 27 before mentioned. It will be obvious that so long as a predetermined degree of expansion of the volatile 15 liquid in the capsule 15 and connected parts is maintained, so long will the lever 18 be held in a position such that the valve 27 is closed, and the valve 28 is opened. When the valve 28 is open, the full pressure of 20 the fluid under pressure, is admitted to the diaphragm chamber of the valve 6 which controls the live steam supply to that section of the dryer, and the valve 6 controlling the live steam supply will be held tightly closed 25 to its seat. The diaphragm chamber of that valve 6 which controls the admission of exhaust steam to that section 3 of the manifold, will have no fluid pressure, because of the fact that the valve 27, controlling the 30 flow of fluid under pressure to the said chamber is held closed. Hence the valve 6 controlling the supply of exhaust steam to that section of the dryer will be held open by its spring, and the full supply of exhaust 35 steam will be admitted to that section of the dryer. Should the temperature of such section fall below the predetermined degree which is indicated on the scale of the dial 26, the volatile liquid will contract, or 40 decrease in volume, and the capsule 15 will contract to correspond with the contraction of the liquid. This will permit the lever 18 to swing under the influence of the spring 21, in a direction to open the valve 27, and to close the valve 28. The extent of movement of the lever 18 determines the amount of fluid under pressure which is admitted to the diaphragm casings controlling the valve 45 of the exhaust supply and that of the live steam supply, and the amount of fluid under pressure admitted to the said diaphragm chambers determines the extent of the opening or closing movement of the valves, so that the live steam controlling valve will be opened or partially opened, and the exhaust steam supply controlling valve will be closed or partially closed, to vary the relative amount of live steam and exhaust steam admitted. So long as the temperature 50 remains at the degree determined, and shown by the scale on the dial 26, so long will the live steam supply controlling valve be closed. When however the temperature falls below this predetermined degree, the lever 18 will be operated to open the live

steam supply valve, to admit live steam to the manifold to supplement the heating action of the exhaust steam. At the same time the supply of exhaust steam will be lessened or cut off.

The fluid under pressure is supplied to the controlling mechanism, by means of a pipe 37 which has branches 38 leading to the duplex and to the simplex controls. In the duplex controls these branches as shown in Figure 1^b 70 are controlled by the valves 28. Branches 39 lead from the branches 38, and these branches are controlled by the valves 27 and in turn control the supply of exhaust steam to the manifold.

A board 40 is provided for each section of the dryer, and upon these boards is mounted the simplex or duplex controller, as the case may be. In addition each board carries a temperature recorder indicated at 41, and an air pressure recorder 42. Pressure gages 43 are arranged in the pipes 13 and 39, a gage being arranged in the pipe 13 on each side of the valve 27, and these gages indicate the pressure in the several 80 lines. A dial steam inlet pressure gage 44 and a dial thermometer 45 are also provided in connection with each board. The instruments 41 and 45 are connected to the 85 thermostat in the selected cylinder, in the same manner as is the capsule 15. By 90 means of these instruments we have a complete record of the entire drying operation. When the temperature has been determined for a certain weight of paper, it is only 95 necessary to set the mechanisms to that point, and like results at different intervals and with different operators will be attained.

At that end of the exhaust header 2 remote from the engine, and in each pipe 4 adjacent to the header, there is arranged a steam separator 46. A pipe 47 leads from the separator at the end of the exhaust pipe remote from the engine to a steam trap. At 105 the opposite end of the exhaust header there is provided a back pressure or emergency valve. A branch pipe 48 leads from the header to a pipe 49, whose one end is connected to the feed water heater, the back 110 pressure valve indicated at 50 being arranged at the other end of the pipe. The valve 50 is a safety valve, designed to open under a predetermined pressure within the header, and a valve 51 is arranged between 115 the branch 48 and the feed water heater for controlling the communication of the header with the heater. This valve 51 is of the same construction as that shown in Figure 5, but it is so arranged that the spring 52 thereof encircling the stem 53 normally holds the valve closed. That end of the stem remote from the valve is connected 120 with a diaphragm in a diaphragm chamber 54. This chamber is supplied with fluid 125

4
 under pressure through a pipe 55, and the communication of the pipe 55 with the supply pipe 47 for fluid under pressure is controlled by a simplex controller 56 of the character just described. This controller is arranged on a board 57 similar to the boards 40, and the said board 57 carries gages 58 and 59 recording the back pressure and the pressure of the main air supply respectively. 10 The board also carries a back pressure gage 60. When the paper machine for any reason is shut down, the exhaust controlling valves in the pipes 4 will close, and the valve 51 will open, thus permitting the condensate 15 to pass to the feed water heater, and these operations will be recorded by the several instruments above mentioned.

In order to insure a rapid circulation of steam through the dryer, and consequent 20 elimination of dead air and steam pockets, and to remove the condensate as it is formed, we provide the mechanism shown in Figures 2^a and 2^b. At the opposite side of the dryer from the exhaust manifold sections, we provide 25 a manifold, consisting of connected sections 61, which are separated by valves 62, and each section 61 of the manifold is connected with the cylinders of a section of the dryer. The manifold sections 61 are 30 connected to the cylinders by branch pipes 63 which place the interior of the cylinders in communication with the manifold sections. A separator 64 is arranged in each 35 branch, near the top thereof, and each separator has a pair of inclined baffles 65 and 66 which are spaced apart and parallel, as shown in Figure 6. The flow from the cylinder 1 will enter the casing of the separator 64 and the condensate will form a seal at the 40 bottom of the baffle 65. It will be noted referring to Figure 6 that the lower end of this baffle 65 is below the upper end of the baffle 66. A gas and vapor outlet pipe 67 leads from each separator to a collector 68 45 adjacent to the cylinder, and the collector 68 leads to a vacuum pump to be later described. The manifold sections 61 communicate by means of pipes 69 with float chambers 70 of the character shown and described 50 in Patent No. 1,196,020, granted August 29, 1916. The said chambers communicate by means of pipes 71 with the sections 72 of a drip header, the several sections being separated by valves 73. Thus 55 each section of the manifold 61 communicates with an adjacent section 72 of the drip header. Valves 74 and 75 are arranged in the pipes 69 and 71 respectively for permitting 60 said pipes to be controlled manually when desired. The flow through the pipe 71, which is a discharge pipe for the manifold section, is controlled by a valve similar to the valve 6 of Figure 5, and arranged in a similar casing 76 interposed in the length 65 of the same. Each of these valves has a

stem 77 and is normally held closed by a spring as shown, and is connected with a diaphragm in a diaphragm chamber 78. Fluid under pressure is supplied to each diaphragm chamber by means of a branch 79 from a common pipe 80, and the flow through each pipe 79 is controlled by a valve not shown, which is operated by the float in the float chamber 70. When the level of the liquid in the float chamber attains a predetermined point, fluid under pressure will be admitted to the diaphragm chamber, and the valve will be opened, permitting the condensate to flow from the float chamber into the drip header. The air and vapor is 80 separated from the condensate by separators shown in Figure 6, and is returned by way of the collectors 68 to the feed water heater indicated at 81. The collector 68 opens into a pipe 82 which connects the adjacent end of the drip header 72 to the feed water heater, and the vacuum pump indicated at 83 is so connected to this pipe 82, that the flow from the header may be direct to the feed water heater, or by way of the vacuum pump. Referring to Figure 2^a it will be seen that the vacuum pump is arranged in a by-pass 84, and that valves 85 are provided for closing the by-pass, or for closing the pipe 82 between the ends of the by-pass. At its opposite end the drip water header delivers to the boiler 86, the flow being controlled by a crane tilt trap indicated at 87. A valve controlled connection 88 is arranged at the said end of the drip header, for connecting said header to the heating system.

Fluid under pressure, in the form of compressed air is supplied from a storage tank 89. A purifier 90 is interposed in the supply pipe 80 between the storage tank and the mechanisms which the fluid under pressure operates, and compressed air is supplied to the storage tank, by means of a compressor 91 or a compressor 92. The former is a belt or steam driven compressor, while the latter is an electrically controlled compressor, being driven by a suitable motor 93. It will be understood that the pipe 37 also derives its supply from the tank 89.

The operation of the improved temperature controller is as follows:—

The pointer or indicator 25 of the master board pertaining to each series of cylinders is set at the temperature which it is desired to maintain in the set of cylinders. In the simplex controllers when the temperature of the cylinders exceeds the degree desired, or falls below the same, the valve 27 will be actuated to increase or decrease the supply of fluid under pressure to the diaphragm chamber of that valve 6 which controls the supply of heating fluid to that series of cylinders. With the duplex controller whenever the supply of exhaust steam is insuffi-

cient to maintain the desired degree of temperature, the lever 18 will be actuated to open the valve 28, to admit live steam to the manifold of the series. So long as the desired degree of temperature is maintained by the exhaust steam, no live steam is admitted. The exhaust from the cylinders passes into the drip header sections, the vapor and air being separated from the condensate by the separators, and such air and vapor is returned to the feed water heater, where it is vented to the atmosphere through a vent 94. The condensate is returned to the boiler or to the feed water heater. The improved controller is controlled by the temperature of the cylinders, and is not dependent upon steam pressure, nor upon the movement of the web. Each series of cylinders may be set to be heated to a predetermined degree, and the temperature of the series is progressively increased from the wet end to the dry end of the dryer.

It will be noted that all of the separators 64 are connected by the pipe 67 with the vacuum pump 83, and this pump maintains in each cylinder a reduced pressure or partial vacum, permitting a continuous outlet of steam and vapor and possibly some condensate to the water heater 81. This arrangement is directly responsible for the rapid circulation of the steam within the drying cylinders, and for the elimination of dead air and steam pockets.

We claim:

1. In paper making machines, the combination with the drying cylinders and the means for heating the same, of auxiliary heating means, and means controlled by the temperature of selected cylinders for connecting and disconnecting the auxiliary heating means to the cylinders.

2. In a paper making machine, the combination with the drying cylinders, and the exhaust steam supply for heating the cylinders, of means controlled by the temperature of the cylinders for regulating the supply to maintain a predetermined temperature, and auxiliary means controlled by the temperature of selected cylinders for admitting live steam to the cylinders when the temperature of the selected cylinders falls below a predetermined degree.

3. In a paper making machine, the combination with the drying cylinders, and the exhaust steam supply for heating the cylinders, of an auxiliary live steam supply, and means controlled by the temperature of selected cylinders for connecting and disconnecting said live steam supply with the cylinders.

4. In a paper making machine, the combination with the drying cylinders and the exhaust steam supply for heating the cylinders, of means controlled by the temperature of selected cylinders for admitting the

steam to the cylinders in accordance with the needs the eof to maintain a substantially uniform temperature.

5. In a paper making machine, the combination with the drying cylinders and the exhaust steam supply for heating the cylinders, of means controlled by the temperature of selected cylinders for admitting the steam to the cylinders in accordance with the needs thereof to maintain a substantially uniform temperature, a live steam supply and means controlled by the temperature of selected cylinders for connecting and disconnecting the live steam supply with the cylinders.

6. In paper making machines, the combination with the drying cylinders, of automatically controlled means for heating said cylinders to progressively higher temperatures from the wet to the dry end.

7. In paper making machines, the combination with the drying cylinders, of means for heating said cylinders to progressively higher temperatures from the wet to the dry end, and means controlled by the temperature of selected cylinders for maintaining the temperature of the cylinders substantially uniform.

8. In paper making machines, the combination with the drying cylinders, of means for heating said cylinders to progressively higher temperatures from the wet to the dry end, means controlled by the temperature of selected cylinders for maintaining the temperature uniform, and means for adjusting said last named means to vary the predetermined temperature.

9. In paper making machines, the combination with the drying cylinders, of means for heating groups of selected cylinders independently of the cylinders of other groups, and controlled by the temperature of a selected cylinder of the group to maintain the temperature of the cylinders of the group uniform and at a predetermined degree.

10. In paper making machines, the combination with the drying cylinders, of means for heating groups of selected cylinders, controlled by the temperature of a cylinder of the group, and independently adjustable whereby to provide for different temperatures in the several groups.

11. In paper making machines, the combination with the drying cylinders, of a common heating means for the cylinders, and means controlled by the temperature of cylinders selected from the series at intervals for connecting and disconnecting said cylinders and adjacent cylinders to the heating means.

12. In paper making machines, the combination with the drying cylinders, of a common heating means for the cylinders, means controlled by the temperature of cylinders selected from the series at intervals for con-

necting and disconnecting said cylinders and adjacent cylinders to the heating means, each of the said means being independently adjustable to provide for progressively higher temperatures from the wet to the dry end.

13. In paper making machines, the combination with the drying cylinders, of a common heating means for the cylinders, means controlled by the temperature of cylinders selected from the series at intervals for connecting and disconnecting said cylinders and adjacent cylinders to the heating means, each of the said means being independently adjustable to provide for progressively higher temperatures from the wet to the dry end, auxiliary heating means, and means in connection with sundry of said selected cylinders and controlled by the temperature thereof for connecting and disconnecting the auxiliary heating means and the cylinders.

14. In a machine of the character specified, the combination with the drying cylinders, and the steam supply for heating the same, of a common drip header for the cylinders, a return pipe for the condensate, and means controlled by the liquid level in the return pipe for controlling the flow of liquid from the header to the return pipe.

15. In a machine of the character specified, the combination with the drying cylinders, and the steam supply for heating the same, of a common drip header for the cylinders, a return pipe for the condensate, means controlled by the liquid level in the return pipe for controlling the flow of liquid from the header to the return pipe, and means interposed between the cylinders and the drip header for separating the air and vapor from the liquid.

16. In paper making machines, the combination with the drying cylinders, of means controlled by the temperature of selected cylinders for maintaining the temperature

of the cylinders uniform, and means for removing vapor from the cylinders to prevent air pockets and the like.

17. In paper making machines, the combination with the drying cylinders, of means controlled by the temperature of selected cylinders for maintaining the temperature of the cylinders uniform, means for removing vapor from the cylinders to prevent air pockets and the like, a drip header connected with the cylinders for receiving the condensate therefrom, and means controlled by the level of the liquid condensate for gradually removing the same from the header.

18. In a paper making machine, the combination with the drying cylinders, and the means for supplying a heating fluid to the cylinders to heat the same, of means for controlling said supplying means to maintain a substantially uniform temperature of the cylinders, fluid pressure controlled means for operating the said controlling means, said means including a volatile liquid subjected to the heat of the cylinders and an expansible and contractable element in which the liquid is held.

19. In a machine of the character specified, the combination with the drying cylinders, and means for supplying steam thereto to heat the same, of means for maintaining a partial vacuum in the said cylinders for the purpose specified.

20. In paper making machines, the combination with the drying means, of means for heating the same, auxiliary heating means, and means directly responsive to the temperature of the drying means for connecting and disconnecting the auxiliary heating means.

In testimony whereof we affix our signatures.

GEORGE STANFORD WITHAM, Jr.
GEORGE STRONG WITHAM, Sr.
